UNITED STATES PATENT OFFICE

ALBERT H. BATES, OF ROCKFORD, ILLINOIS, ASSIGNOR TO BURD HIGH COMPRESSION RING COMPANY, OF ROCKFORD, ILLINOIS, A CORPORATION OF ILLINOIS

AUTOMOBILE HEATER

Application filed April 13, 1928. Serial No. 269,631.

This invention relates to automobile heaters and more particularly that class which utilizes the heat in the water of the engine cooling system.

The principal object of the invention is to provide a highly efficient heater of the kind referred to which is so designed and arranged to be so installed that circulation of heated fresh air is positively induced in the tonneau of the automobile, and there is never any danger of fumes being carried in, as is the case with many heaters using the heat of the exhaust gases.

According to my invention a radiator connected with the water cooling system is mounted on the dash and has an air supply conduit connected therewith, the said conduit in one form of my invention having the intake end thereof disposed directly in back of the automobile radiator near the motor fan so as to insure an induced draft of pure fresh air through the heater radiator, and the said conduit in another form of my invention being supplied with pure fresh air from the same or any other suitable source and having an electric fan operated in connection therewith to induce the draft of fresh air through the heater radiator, the ratio of the amount of air introduced to the area of exposure of the radiator in either case being such that a comfortable temperature is maintained in the car even in the coldest weather.

Among the special features incorporated in the heater of my invention may be enumerated the following:

1. The provision of a heater radiator having water supply and return pipes connected to the top and bottom of the radiator, respectively, and anchored to the dash so as to form a rigid support for the radiator and thus avoid the necessity of additional means for such purpose.

2. The provision in connection with the heater radiator supported by the water supply and return pipes, as just indicated, of an electric fan behind the radiator supported on a bracket carried by one or both of said pipes.

3. The provision of a shroud for the back of the heater radiator connected with the air supply conduit, and, in the one form of the

invention, having the electric fan disposed therein, the said shroud being open on the under side to entrain cold air from the floor in the air draft through the radiator and thus induce air circulation in the car.

4. The provision of an air valve suitably controlled from the instrument board by an operating cable extended through the core of the heater radiator. If desired, I may also provide means for regulating the opening on the under side of the radiator shroud so as to control the recirculation of air in the car.

The invention is illustrated in the accompanying drawings wherein—

Figure 1 is a section through the front end of an automobile showing one type of installation of my improved heater;

Fig. 2 is an enlarged section through the radiator end of the device;

Fig. 3 is a somewhat similar view showing a different dash mounting for the heater; and

Fig. 4 is a still further enlarged section, similar to Fig. 2, of another type of installation showing the use of an electric fan for inducing the draft of fresh air through the heater radiator.

Similar reference numerals are applied to corresponding parts throughout the views.

Referring first to Figs. 1 and 2, the heater, briefly stated, comprises a radiator 5 having a sheet metal shroud 6 on the back thereof, an air supply conduit 7 communicating with the shroud and extending forwardly to an air intake funnel 8, supply and return pipe connections 9 and 10, respectively, for the hot water, and air regulating means 11. The radiator 5 is of suitable proportions and comprises a core 12, of any preferred or standard construction, between top and bottom headers 13 and 14, respectively, forming a part of the shell thereof. The radiator is suitably covered on the exposed front thereof by an ornamental face plate 15. The shroud 6, which is funnel-shaped, is fastened suitably to the back of the radiator shell, as appears in Fig. 2, and is fastened at the smaller end thereof to a short tube 16 passed preferably freely through a hole 17 in the dash 18. The radiator 5 may be, but is preferably not, part-

ly supported by the tube 16. In the present case, as shown, the principal support for the radiator is provided by the pipes 9 and 10, which pass through holes 19 and 20, respectively, provided in the dash 18, and are suitably clamped by nuts 21 and 22 threaded on the pipes on opposite sides of the dash. The pipes 9 and 10 make connection with the headers 13 and 14, respectively, by threading into hollow reinforcing castings 23 and 24 disposed inside the headers. The mounting of the radiator is, therefore, absolutely firm and does not permit any vibration and consequent rattling of the radiator when the car is in motion, nor is there any danger of water leakage due to joints loosening. The pipes 9 and 10, as stated above, constitute the supply and return pipe connections for the hot water and have hoses 24 and 25, respectively, fastened thereto and clamped as indicated at 26 and 27. The hose 24 leads to a cock 28 screwed into a hole tapped into the motor head at the point where the water is hottest. When the hood 29 is raised the cock 28 is easily accessible for opening and closing the same. The hose 25 taps into the lower outlet hose connection 30 of the radiator 31, between the radiator 31 and the water pump 32. Any suitable form of connection, as represented at 33, may be employed. By reason of the connections just described, it will be evident that water at the highest obtainable temperature is supplied to the radiator 5 from the motor 34 through the hose connection 24, as indicated by the small arrow, and that the water flows downwardly through the radiator and through the hose connection 25 back to the cooling system, as indicated by the small arrow. In warm weather the heater may be entirely shut off by closing the cock 28. If desired, the operation of the heater may be regulated partly by regulating the opening of the cock 28. However, it is more practical to regulate the heater by controlling the air blast as will now be described.

The air conduit 7 is in the form of a tube or hose fitted onto the tube 16 and clamped as indicated at 35. The said conduit extends to the front end of the motor 34 where it is suitably supported by a clip 36. The air intake funnel 8, clamped to the forward end of the conduit 7, as shown at 37, is disposed immediately behind the motor fan 38 and preferably entirely within the fan circle to get the full benefit of the action of the fan. The funnel 8 obviously collects nothing but pure fresh air, uncontaminated by any fumes from the motor, and this air flows through the conduit 7 to the radiator 5, to be heated on passing therethrough into the tonneau of the car. While the major part of the heating is due to the radiator 5, it should be evident that the efficiency of the heater is promoted, at least to some degree, by reason of the fact

that the air used is raised slightly above outside temperature by reason of its passage through the core of the radiator 31, especially through the upper portion thereof, and also that the air, in passing through the conduit 7 to the heater, is raised in temperature to a certain extent by reason of its having to pass almost directly over the hottest part of the motor the full length thereof. The air blast through the radiator 5 draws in air through a fairly large opening 40 provided in the lower side of the shroud 6, this air being cold air drawn from the floor. The air in the car is never stagnant, therefore, but is constantly kept in circulation, which, of course, makes for the most comfortable heating as well as the most healthful condition. The efficiency of the heater is such that in moderate weather it would be uncomfortably warm in the car if no means were provided for regulating the operation of the heater. For that reason I prefer to provide a butterfly valve 41 in the tube 16 having a flexible wire or cable 42 attached thereto at the inner end, as shown at 43, and having a button 44 mounted on the other end thereof and disposed within easy reach of the driver, suitably at some point on the instrument board 45. A bracket 46 arranged to be clamped onto the instrument board, as indicated at 47, has a flexible tube 48 attached thereto and extended through the core 12 of the radiator 5 to serve as a guiding conduit for the wire 42.

The operation of the heater is believed to be perfectly evident from the foregoing description so that additional explanation seems unnecessary. The drawing illustrates graphically by the use of long arrows the path of the fresh air drawn in by the motor fan 38 through the radiator 31 and forced through the conduit 7 for passage through the radiator 5 into the tonneau of the car, and by shorter arrows how the air in the car is recirculated.

In Fig. 3, I have shown a modified or alternative construction which has the advantage over that just described of necessitating only a single hole being cut through the dash for the installation of the heater. The tube 16' passed through the hole 17 in the dash 18 is braced by the bolting of collars 49 and 50 onto opposite sides of the dash. In place of the straight pipes 9 and 10 used in the other form, the pipes 9' and 10' are provided which are bent inwardly toward each other and passed through openings 51 and 52, respectively, provided in the walls of the tube 16'. The pipes 9' and 10', at some point in front of the dash are led out through openings in the air conduit to make connection with the engine cooling system in some such manner as previously described.

In the type of installation shown in Fig. 4 the heater radiator 5 is supported from the dash 8 by the supply and return pipes 9 and

10, respectively, similarly as shown in Fig. 2. In this case, however, the air supply conduit 7 communicating with the tube 16 may or may not be extended to a point near the motor fan 38, as shown in Fig. 1, inasmuch as the proper air draft through the radiator 5 is insured by the operation of a fan 53 which, with its electric motor 54, is mounted within the shroud 6', as shown. In other words, the air supply conduit may be led to any convenient source of supply of pure fresh air and the fan 53 will insure the drawing in of an adequate supply of such air and the forcing of the same through the core 15 of the radiator into the tonneau of the car. The motor 54 is shown supported by a bracket 55 clamped as by means of bolts 56 to one of the water pipe connections, in this case the pipe 10. Either one or both of the pipe 20 connections may be used to support the motor. The pipe connections, therefore, serve a triple function, they conduct the hot water to and from the heater radiator, support the radiator from the dash, and form a support for the electric motor 54. The motor 54 will, of course, be connected with the battery of the car in the usual way and have a suitable switch for turning the same on and off. The air supply is arranged to be regulated in this 25 case, as in the other cases, by the extension of a cable or wire 42 through the core of the radiator 5 to the butterfly valve 41, the wire 42 being operated suitably from the instrument board, or from directly in front of the radiator if desired. In this case, as in the other cases, the under side of the shroud 6' has an opening 40' to permit entraining cold air from the floor in the air draft through the 30 radiator so as to induce circulation and recirculation of air in the car. A flap valve 57, pivoted at 58, may be provided to regulate the amount of recirculation accordingly as the prevailing outdoor temperatures may dictate. For example, in extremely cold weather it may be found preferable to keep the butterfly valve 41 only part way open or even entirely closed, and accordingly open the valve 57 to a greater extent than would be found desirable in warmer weather. An outstanding advantage in the use of an electric 35 fan for inducing the air draft as compared with relying on the motor fan for that purpose is that the air draft will be stronger as well as substantially uniform, and that the operation of the heater will be attended with less noise.

It is believed the foregoing description conveys a clear understanding of my invention and of all of its objects and advantages. While I have shown and described the invention as applied to two specific embodiments it should be understood that certain changes in design and construction will naturally suggest themselves to those skilled in the art to which the invention relates, as a result of the

present disclosure. For that reason all legitimate modifications and adaptations coming within the spirit and scope of the invention are intended to be covered in the appended claims.

I claim:

1. A device of the character described comprising a radiator arranged to be mounted on a suitable supporting wall in the tonneau of an automobile or other vehicle, supply and return pipes having rigid connection with opposite ends of said radiator for conducting the heating medium to and from the same, the said connections being ample for the support of the radiator by the pipes alone, means for fastening the pipes rigidly to the wall whereby to support the radiator on said wall, means for supplying the heating medium for passage through the radiator by way of the supply and return pipes, and means for supplying air to the radiator for passage therethrough.

2. A device of the character described comprising a radiator arranged to be mounted on the dash or other suitable supporting wall in the tonneau of an automobile or other vehicle, an electric motor operating a fan to force air through said radiator, supply and return pipes having rigid connection with opposite ends of said radiator for conducting the heating medium to and from the same, the said pipes constituting the sole support for the radiator together with the motor and fan, means for fastening the pipes rigidly to the wall whereby to support the assembly on said wall, and means for supplying the heating medium for passage through the radiator by way of the supply and return pipes.

3. A device as set forth in claim 1 wherein the radiator comprises a core for the passage of air therethrough and headers at the opposite ends of said core communicating with the supply and return pipes for supplying and exhausting the heating medium from the core, and including reinforcing members disposed within and rigid with said headers and having the pipes rigidly connected therewith and in communication with the headers.

4. A device of the character described comprising a radiator arranged to be mounted on a suitable supporting wall in the tonneau of an automobile or other vehicle, supply and return pipes for conducting the heating medium to and from the radiator, said pipes having connection with opposite ends of the radiator and being mounted rigidly on the wall whereby to provide support for the radiator, a shroud on the back of said radiator having an air intake opening, a fan in said shroud for forcing air through the radiator, an electric motor for driving the fan, and a bracket borne by at least one of said pipes serving to support the motor.

5. A device of the character described comprising a radiator arranged to be mounted on

- 5 a suitable supporting wall in the tonneau of an automobile or other vehicle, supply and return pipes having rigid connection with opposite ends of said radiator for conducting the heating medium to and from the same, the said connections being ample for the support of the radiator by the pipes alone, means for fastening the pipes rigidly to the wall whereby to support the radiator on said wall, a fan and electric motor for driving the same disposed behind the radiator and arranged when operated to force air therethrough, and means borne by at least one of said pipes for supporting the motor with its fan in proper relation to the radiator.
- 10 6. A device of the character described comprising a radiator arranged to be mounted on a suitable supporting wall in the tonneau of an automobile or other vehicle, supply and return pipes for conducting the heating medium to and from the radiator, said pipes having connection with opposite ends of the radiator and being mounted rigidly on the wall whereby to provide support for the radiator, a shroud for delivering air to the back of the radiator for passage therethrough, said shroud having an air intake opening, a fan and electric motor for driving the same disposed within the shroud for inducing the draft of air through the radiator, and a bracket for supporting the motor carried by one of said pipes.
- 15 7. A device of the character described comprising a radiator arranged to be mounted in the tonneau of an automobile or other vehicle, means whereby the radiator is heated, a shroud for the back of the radiator, and an air conduit communicating with the shroud for supplying fresh air thereto from without the tonneau for passage through the radiator, said shroud having an opening therein to entrain air from within the tonneau in the air draft through the radiator for the purpose described.
- 20 8. A device of the character described comprising a radiator arranged to be mounted in the tonneau of an automobile or other vehicle, means whereby the radiator is heated, a shroud for the back of the radiator, and an air conduit communicating with the shroud for supplying fresh air thereto from without the tonneau for passage through the radiator, said shroud having an opening through the bottom wall thereof to entrain cold air from the floor within the tonneau in the air draft through the radiator whereby to induce circulation of warm air substantially as described.
- 25 9. A device of the character described comprising a radiator arranged to be mounted in the tonneau of an automobile or other vehicle, means whereby the radiator is heated, and a shroud for the back of the radiator disposed substantially wholly within the tonneau, said shroud having an air intake opening supplied with air from the outside of the tonneau, and another air intake opening communicating with the inside of the tonneau, the former being for the supply of cold fresh air from without the tonneau, and the latter being for the recirculation of air within the tonneau.
- 30 10. A device as set forth in claim 9 including a manually operable valve arranged to be operated whenever desired to regulate or shut off the flow of air through the first mentioned opening.
- 35 11. A device as set forth in claim 9 including a manually operable valve arranged to be operated whenever desired to regulate or shut off the flow of air through the first mentioned opening, and means for regulating the flow of air through the other opening, said means being arranged to be set in different positions for more or less permanently controlling the amount of recirculation.
- 40 12. A device of the character described comprising a radiator arranged to be mounted in the tonneau of an automobile or other vehicle, means whereby the radiator is heated, a shroud for the back of the radiator, said shroud having an air intake opening communicating with the outside of the tonneau, and a power-driven fan disposed within said shroud for impelling air through the radiator, said shroud having another opening on the suction side of the fan through which air is arranged to be drawn in the operation of said fan, said opening communicating with the inside of the tonneau and causing the entraining of air from within the tonneau in the air draft through the radiator.
- 45 13. A device as set forth in claim 12 including a valve arranged to be manually operable at will to regulate the flow of air through the first mentioned opening.
- 50 14. A device as set forth in claim 12 including a valve arranged to be manually operable at will to regulate the flow of air through the first mentioned opening, and another valve means for controlling the flow of air through the other opening.
- 55 15. A device as set forth in claim 12 including adjustable means for regulating the flow of air through the last mentioned opening.
- 60 16. A device of the character described comprising a radiator arranged to be mounted in the tonneau of an automobile or other vehicle, means whereby the radiator is heated, a shroud for the back of the radiator, said shroud having an opening communicating with the inside of the tonneau, and a power-driven fan disposed within said shroud for impelling air through the radiator, the shroud opening being on the suction side of the fan so that air is arranged to be drawn in through said opening in the operation of said fan.

17. A device as set forth in claim 16 including means for regulating the passage of air through said opening.

18. A device as set forth in claim 16 wherein in the radiator is arranged to be so disposed that said shroud opening is below the point of warm air discharge whereby to induce better circulation of air in the tonneau.

19. A device of the character described comprising a radiator arranged to be mounted on the dash in the tonneau of an automobile or other vehicle, means whereby said radiator is heated, a funnel-shaped shroud for the back of the radiator, an air conduit communicating with the small end of the funnel-shaped shroud and arranged to supply air thereto for passage through the radiator, an air valve for controlling the flow of air into said shroud, said valve being of the butterfly type, and a cable having connection with the valve and extending through the core of the radiator whereby to permit the operation of said valve from the front of the radiator.

20. A device of the character described comprising a radiator arranged to be mounted in the tonneau of an automobile or other vehicle, means whereby the radiator is heated, and a shroud for the back of the radiator disposed substantially wholly within the tonneau, said shroud having an air intake opening supplied with air from the outside of the tonneau, another air intake opening communicating with the inside of the tonneau, the former being for the supply of cold fresh air from without the tonneau, and the latter being for the recirculation of air within the tonneau, and means for regulating the flow of air through the last mentioned intake opening.

21. A device of the character described comprising a radiator arranged to be mounted on the dash in the tonneau of an automobile or other vehicle, means whereby said radiator is heated, a funnel-shaped shroud for the back of the radiator, an air conduit communicating with the small end of the funnel-shaped shroud and arranged to supply air thereto for passage through the radiator, an air valve for controlling the flow of air into said shroud, said valve being of the butterfly type, and a cable having connection with the valve and extending through the core of the radiator whereby to permit the operation of said valve from the front of the radiator, said shroud having an opening therein to entrain air from within the tonneau in the air draft through the radiator for the purpose described.

22. A device of the character described comprising a radiator arranged to be mounted on the dash in the tonneau of an automobile or other vehicle, means whereby said radiator is heated, a funnel-shaped shroud for the back of the radiator, an air conduit communicat-

ing with the small end of the funnel-shaped shroud and arranged to supply air thereto for passage through the radiator, an air valve for controlling the flow of air into said shroud, said valve being of the butterfly type, 70 a cable having connection with the valve and extending through the core of the radiator whereby to permit the operation of said valve from the front of the radiator, said shroud having an opening therein to entrain air from within the tonneau in the air draft through the radiator for the purpose described, and means for regulating the flow of air through the last mentioned opening.

23. A device of the character described comprising a radiator arranged to be mounted on the dash in the tonneau of an automobile or other vehicle, means whereby said radiator is heated, a funnel-shaped shroud for the back of the radiator, a power-driven 85 fan in said shroud for forcing air through said radiator, an air conduit communicating with the small end of the funnel-shaped shroud and arranged to supply air thereto for passage through the radiator, an air valve 90 for controlling the flow of air into said shroud, said valve being of the butterfly type, and a cable having connection with the valve and extending through the core of the radiator whereby to permit the operation of 95 said valve from the front of the radiator.

24. A device of the character described comprising a radiator arranged to be mounted on the dash in the tonneau of an automobile or other vehicle, means whereby said radiator is heated, a funnel-shaped shroud for the back of the radiator, a power-driven fan 100 in said shroud for forcing air through said radiator, an air conduit communicating with the small end of the funnel-shaped shroud 105 and arranged to supply air thereto for passage through the radiator, an air valve for controlling the flow of air into said shroud, said valve being of the butterfly type, and a cable having connection with the valve and 110 extending through the core of the radiator whereby to permit the operation of said valve from the front of the radiator, said shroud having an opening therein through which air is arranged to be drawn from within the tonneau into the air draft through the radiator 115 for the purpose described.

In witness of the foregoing I affix my signature.

ALBERT H. BATES. 120
